US00D849142S

(12) **United States Design Patent** (10) Patent No.: **US D849,142 S**
Miceli et al. (45) Date of Patent: **** May 21, 2019**

(54) **PHARMACEUTICAL CLOSURE
COMPLIANCE LABEL**

(71) Applicant: **Tri State Distribution, Inc.**, Sparta, TN
(US)

(72) Inventors: **David A. Miceli**, Reno, NV (US);
Joseph A. Miceli, Spencer, TN (US)

(73) Assignee: **Tri State Distribution, Inc.**, Sparta, TN
(US)

(**) Term: **15 Years**

(21) Appl. No.: **29/615,814**

(22) Filed: **Aug. 31, 2017**

Related U.S. Application Data

(63) Continuation-in-part of application No. 15/221,783,
filed on Jul. 28, 2016, now Pat. No. 9,782,327.

(57) **CLAIM**

The ornamental design for a pharmaceutical closure compliance label, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top view of the pharmaceutical closure compliance label;

FIG. 2 is a perspective view of the pharmaceutical closure compliance label as elevated from its intended position on an exemplary pharmaceutical closure; and,

FIG. 3 is a perspective view of the pharmaceutical closure compliance label in its position on an exemplary pharmaceutical closure.

The broken lines showing the text on the pharmaceutical closure compliance label illustrate portions of the article that form no part of the claimed design. The broken lines

(Continued)

showing a pharmaceutical bottle and closure in FIGS. 2 and 3 illustrate environment and form no part of the claimed design.

**1 Claim, 3 Drawing Sheets
(3 of 3 Drawing Sheet(s) Filed in Color)**
